SPARK PLUG

Thomas Dukelow, Chicago, Ill.

Application May 13, 1937, Serial No. 142,333

2 Claims. (Cl. 123—169)

My invention relates to spark plugs for internal combustion engines and the like.

An object of my invention is to provide a simple, practical, economical and efficient device 5 of the character described.

Another object is to provide a spark plug having greatly improved operating characteristics in which is provided two gaps for the sparking feature.

10 Other objects and advantages will appear and be brought out more fully from the following specification, reference being had to the accompanying drawing wherein:

Fig. 1 is a side view of a spark plug embodying 15 my invention;

Fig. 2 is a similar view partly in central section;

Fig. 3 is a bottom view of the same; and

20 Figs. 4 and 5 are respectively views in section of the inner insulator and electrode.

Referring more particularly to the drawing, I show a spark plug 10 of the conventional type having a metallic shell 11 provided with a cylindrical bore 12, a reduced bore 13, the bores 12 and 13 being merged in a shoulder 14, the bore 25 13 having a lower edge portion 15 in which is provided the usual terminal stud 16. The shell 11 is further provided with an internally threaded portion 17 and an externally threaded portion 18. The plug is provided with the usual portion 30 20 porcelain dielectric 19 having an internal bore 20 for the insulated electrode 21 and is further provided with a cylindrical portion 22 adapted to fit into bore 12 and has the usual tip protecting extension 23 beyond which extends the tip 24 of the electrode 21. A shoulder 25 is formed on dielectric 19 and is adapted to provide a seat for a gasket 26 held in place by bushing 27. The electrode 21 has the usual terminal bolt 28, and a bushing 29 made of any suitable insulating 35 30 material is located in bore 13 and has an internal bore 30, an enlarged bore 31, a shoulder 32, an abutment surface 33 and an outer cylindrical portion 34 from which construction it will be apparent that the bushing 29 is retained in the shell 11 by the downward pressure of the cylindrical portion 22 of the dielectric 19 against the ring 23, the shoulder 14 of shell 11 serving to position the bushing 29 in place. A metallic 40 45 bushing 35 having an internal bore 36 adapted to receive extension 23 is provided with a shoulder 37 and has an outer cylindrical surface 38 adapted to fit into bore 30 of bushing 29. Bushing 35 is provided with an electrode 39 which 50 55 is positioned between the electrode 16 and tip 24 of electrode 21 and it will thus be apparent

that the electrode 39 is located in the usual spark gap which is between electrode 16 and electrode tip 24.

The operation of the invention is believed to be obvious. The provision of the intermediate 5 electrode 39 which is seen to be insulated both from the shell and the electrode 21 and in the normal spark gap of the device it will be seen that two gaps are at once provided for the spark and the resulting operation is such that a much 10 more efficient or hotter spark is provided. Furthermore, upon the failure of either gap to function the remaining gap is certain to become operative and thus the life is greatly extended and its efficiency materially improved.

15 While I have illustrated and described the preferred form of construction for carrying my invention into effect, this is capable of variation and modification without departing from the spirit of the invention. I, therefore, do not wish 20 to be limited to the precise details of construction set forth, but desire to avail myself of such variations and modifications as come within the scope of the appended claims.

Having thus described my invention, what I 25 claim as new and desire to secure by Letters Patent is:

1. A device of the character described comprising a metallic shell having an electrode in a side portion thereof, a central electrode insulated 30 from said shell and adapted to be connected to a source of potential and forming a spark gap with said first electrode, a single auxiliary electrode of uniform small diameter positioned entirely in said spark gap in spaced relation to said first and second electrodes, and a mounting for 35 said auxiliary electrode insulated from said first and second electrodes, said mounting including a bushing within said shell.

2. A device of the character described comprising a metallic cylindrical shell having an electrode extending radially inwardly adjacent the cylindrical end thereof, a dielectric having a central bore and a cylindrical exterior portion adapted to fit within said shell, an electrode in 45 said dielectric having an end portion adjacent said first mentioned electrode, and a metallic cylindrical bushing in said shell and insulated therefrom and provided with a single auxiliary electrode of uniform small diameter having its 50 end portion terminating between said first and second electrodes, said shell bushing and dielectric having correlated shoulders adapted for interfitting attachment.

55 THOMAS DUKELOW.
